UNITED STATES PATENT OFFICE.

EDWIN M. CAMPFIELD, OF RICHMOND, INDIANA.

FLUE-LINING.

1,209,935.

Specification of Letters Patent. Patented Dec. 26, 1916.

Application filed October 7, 1915. Serial No. 54,696.

To all whom it may concern:

Be it known that I, EDWIN M. CAMPFIELD, a citizen of the United States, residing at Richmond, in the county of Wayne and State of Indiana, have invented a new and useful Flue-Lining, (Case B,) of which the following is a specification.

This invention relates to flue linings and is more especially an improvement upon the structure disclosed in my co-pending application, Serial No. 105,663, filed June 24, 1916, one of the objects of the invention being to provide a cellular lining the walls of which are so treated as to render them non-porous, thus to materially reduce the transmission of heat to the bodies of air contained within the cells, and to render the lining more efficient as an insulating medium than would otherwise be the case.

20 A further object is to provide a lining containing small cells which are sealed, when the lining is set up for use, these cells greatly reducing, if not altogether eliminating the circulation of air within the walls of the 25 lining so that the confined bodies of air become "dead" and the air becomes a better insulating medium than if it should be confined in large bodies whereby an extensive movement or circulation of each confined 30 body would be permitted.

With the foregoing and other objects in view which will appear as the description proceeds, the invention resides in the combination and arrangement of parts and in 35 the details of construction hereinafter described and claimed, it being understood that changes in the precise embodiment of the invention herein disclosed, can be made within the scope of what is claimed, without departing from the spirit of the invention.

40 In the accompanying drawings the preferred form of the invention has been shown.

In said drawings:—Figure 1 is a longitudinal section through interfitting sections 45 of a flue lining embodying the present improvements. Fig. 2 is a section on line A—B Fig. 1.

50 Referring to the figures by characters of reference 1 designates the outer member of a flue lining section, this member being of any desired cross-sectional contour. The said member is made of ceramic material or any plastic fire resisting material, the inner and outer faces of the member being rendered non-porous in any suitable manner, as 55 by providing them with glazed finishes. The

inner member 2 of each flue lining section is made of a similar material and is provided, at one end with an outturned flange 3 extending entirely therearound. Longitudinal 60 ribs 4 are formed along the outer face of the member 2 and extend from the flange 3 at one end of the member to the other end of said member. The outer faces of these ribs and of the flange are disposed in the 65 same plane and are adapted, when member 2 is inserted in member 1, to fit snugly against the inner surface of the member 1, thus to provide a flue lining section having air spaces or cells 5 between the two members and the ribs. The outer face of the member 2 and the faces of the ribs thereon are all rendered non-porous, as by glazing so that when the two members are assembled 70 one within the other the walls of the air cells therebetween will be completely glazed, thus to prevent air from seeping through the walls from the interior of the lining to the air cells and from said air cells to the exterior of the lining.

75 In using the flue lining, the inner and outer members are assembled to form a complete section, the inner member being positioned with its upper or flanged end below the upper end of the outer member so that 80 a socket 6 will be provided above the inner member and within the upper portion of the outer member. A suitable cement, indicated at 7, is placed on the upper ends of the two members 1 and 2 thus assembled, after which 85 the inner member 2 of the next adjoining section is placed in the socket 6 and on the cement 7 while the outer member 1 of the next adjoining section thereabove is placed on the cement on the lower member 1. Thus 90 another socket 6 will be formed. The foregoing operation can be continued until the 95 lining has been set up throughout the required height. It will be noted that the members of the two sections come together at points out of alignment and that the air cells of each section are continued downwardly into the socket in the next adjoining section so as thus to constitute means for 100 insulating the joints between the outer members of the sections.

105 It has been found in practice that a flue lining constructed as herein described and assembled in the manner pointed out, constitutes practically a perfect insulating medium. The non-porous faces of the members of the sections prevent the air from 110

seeping through the walls, as before explained. This treatment of the walls of the members likewise reduces the conduction of heat from the interior of the lining to the contents of the cells and from the cells to the exterior of the lining. By dividing the spaces between the members of the sections into comparatively small cells, convection is practically eliminated, the bodies of air being so small that little if any circulation thereof will be set up.

Although the members of the flue lining have been described as provided with glazed surfaces whereby the pores are sealed, it is to be understood that enamel could also be used.

Instead of utilizing the cells for holding dead air, they may be packed with particles of cork, asbestos or other non-conductors of heat suitable for the uses to which the flue lining is put.

What is claimed is:—

A flue lining section including an outer

member, a separate inner member having an outstanding flange extending continuously around one end portion thereof and of uniform width, and longitudinal ribs extending longitudinally along the outer sides of the inner member and merging at one end into the flange, said flange and the ribs fitting snugly against the inner faces of the wall of the outer member to form non-communicating longitudinal air cells open at one end and closed at their outer ends, the flanged end of the inner member being arranged within the outer member and between the ends of said outer member thereby to form a seat in one end of the lining section.

In testimony that I claim the foregoing as my own, I have hereto affixed my signature in the presence of two witnesses.

EDWIN M. CAMPFIELD.
